UNITED STATES PATENT OFFICE.

SAMUEL H. DOLBEAR, OF SAN FRANCISCO, CALIFORNIA.

GUARD FOR CEMENT WORK.

1,238,992.

Specification of Letters Patent.

Patented Sept. 4, 1917.

Application filed April 28, 1915. Serial No. 24,474.

To all whom it may concern:

Be it known that I, SAMUEL H. DOLBEAR, a citizen of the United States, residing at San Francisco, in the county of San Francisco and State of California, have invented certain new and useful Improvements in Guards for Cement Work, of which the following is a specification, reference being had therein to the accompanying drawing.

10 This invention relates broadly to guards and has especial reference to protecting structures for corners, edges, etc., of cement and similar work.

15 The primary object of the invention is to present a protector which combines with the feature of simplicity that of effectiveness, and yet is inexpensive in its production.

Another object is to provide a protector or guard which includes an exposable head-portion 20 of relatively large dimensions, a foot-portion comprising outspread sections with an intervening groove having a surface of substantial area, and a web-portion connecting the head and foot portions and comparatively thin in cross-section.

The invention contemplates other objects and possesses resultant advantages, all as will be pointed out in the following specification and set forth in the annexed claims.

25 The invention resides broadly in the feature of construction and relative arrangement of the parts thereof, all as will be exemplified in the construction hereinafter set forth, and the scope of application of which 30 will be indicated in the claims hereto appended.

The accompanying drawings are illustrative of one of the many possible utilizations of the invention and are appended 40 hereto as a part of its disclosure. It will be manifest that other possible utilizations and embodiments employing the underlying principles of the invention may be resorted to and be within the spirit thereof and within 45 the objects contemplated thereby.

In these drawings:

Figure 1 is a view in vertical transverse section of a section of cement-work with my improved form of corner-protector embedded therein;

Fig. 2 is a view in perspective of a section of the protector; and

Fig. 3 is a sectional view of a modification.

55 Referring to the drawings, the reference-character 1 designates the exposed or head-

portion of the device; 2 the shank or web-portion thereof; and 3 the foot or anchor-portion.

Preferably and as shown, the web-portion 2 is comparatively thin and of little width, though the dimensions thereof may be such as to meet requirements in any particular instance. The exposed and anchor portions, on the other hand, are of relatively different dimensions from those of the web. Preferably the outer surface of the portion 1 is round and terminates in two oppositely-disposed corner-sections 4, 4. The guard's widest dimensions approximate the 65 distance between the extremities 5, 5 of these two corner-sections.

Extending from the extremities 5, 5 are arcuately cut surfaces 6, 6 that terminate in angularly disposed approximately flat surfaces 7, 7 which, in turn, extend to the extremities 8, 8 of fork-sections 9, 9 that form the foot-section 3.

Formed between the fork-sections is an elongated groove 10 which, as shown in Figs. 1 and 2, is concaved; though, as shown in Fig. 3, it may be V-shaped. The groove is of substantial depth to present a surface of relatively great area, and for a purpose presently to be explained. The sections 9, 9 85 preferably are relatively thinner than the web-section.

As shown, the device is so embedded in the cement 0 that the portion 1 occupies a position longitudinal of the curb or other edge 90 to protect it, while the portion 3 firmly anchors the whole structure in the cement.

It is a further feature of the invention to present a plurality of elongated surfaces, angularly arranged relatively, whereby a blow or impact against any portion of the exposed surface of the head-portion will be distributed in proper proportion to the abutting surfaces of the structure. To this end the fork sections 9 are so related to the arcuately cut portions of the head section that lines drawn to form continuations of the flat surfaces 7, 7 will form tangents on the inner surfaces of the curve portions and intersect at approximately the center of the web portion. Due to this construction, the force of a blow, delivered at the corners of the head portion, will be transmitted in approximately a direct line through the flange on the opposite side, while force delivered to the center of the head portion is transmitted directly through 105 110

the web 2. In this way vibrations of the parts are virtually eliminated, and the tendency of the protector to crack, split or fracture the cement is practically prevented.

5 It will now be perceived that I have succeeded in devising a cement-work guard or protector which is well adapted to achieve the objects and ends in view. The structure is simple and compact in form, and can be
10 made by any convenient method.

As many changes can be made in the construction and form and many other widely different embodiments of the invention can be made without departing from the scope
15 and spirit thereof, it is intended that all matter contained in the foregoing description and shown in the accompanying drawings shall be interpreted as illustrative and not in any limiting sense. It is also to be
20 understood that the language used in the following claims is intended to cover all of the generic and specific features of the invention which as a matter of language might be said to fall therebetween.

25 What I claim is:

1. A protecting guard for cement work and the like, including an exposable head-portion; a foot-portion comprising two out-spreading spaced-apart fork-sections with
30 a V-shaped groove formed therebetween; and a web-portion connecting the head and foot portions and of a thickness substantially less than that of the head-portion; said fork-sections being of a thickness less

than that of the web-portion and having
35 their outspread extremities in approximate alignment with the oppositely disposed portions of the curved surfaces of the head portion; the surfaces of the guard between the extremities of the head-portion and the extremities of the fork-sections being curved, continuous and uninterrupted; whereby the guard, when embedded in the cement, is embraced at its sides on unangular surfaces
40 that effect no splitting or cracking of the cement.

2. A protecting guard for cement and similar work, including an exposable head-portion having corner-sections, a foot-portion comprising outwardly extending, spaced-apart sections and formed with an intervening elongated concaved groove and a web-portion connecting the head and foot portions, each side of the guard between the extremity of an outwardly extending
45 section and the corner-section of the head-portion being formed with a curved surface of substantial length and a flat surface also of substantial length, said side of the guard presenting a continuous and uninterrupted
50 surface.

In testimony whereof I affix my signature in presence of two witnesses.

SAMUEL H. DOLBEAR.
